UNITED STATES PATENT OFFICE

94,669

DESIGN FOR A FACE PLATE FOR SIGNS

Charles B. Drake, Norfolk, Va., assignor to Neon-Globe Co., Inc., Norfolk, Va., a corporation of Virginia

Application September 30, 1933, Serial No. 49,387

Term of patent 3½ years

To all whom it may concern:

Be it known that I, Charles B. Drake, a citizen of the United States, residing at Norfolk, in the county of Norfolk and State of Virginia, have invented a new, original, and ornamental Design for Face Plate for Signs, of which the following is a specification, reference being had to the accompanying drawing, forming part thereof.

In the drawing:

Fig. 1 is a face view of a face plate for signs showing my new design.

Fig. 2 is an edge view; and

Fig. 3 is a fragmental detail showing a portion of the plate as indicated between the lines *a—b* in Fig. 1.

In the drawing the shaded portions are translucent whereas the unshaded portions are transparent, providing adjacent the marginal edge a transparent portion confining a plurality of rows of circumferentially spaced translucent spots or squares, and it will be understood that the design shown between the lines *a—b* of Fig. 1 will be continued around the circumference. The plate is of substantially uniform thickness throughout.

I claim:

The ornamental design for a face plate for signs as shown and described.

CHARLES B. DRAKE.
